UNITED STATES PATENT OFFICE.

JAMES DRONSFIELD, OF OLDHAM, ENGLAND.

MULTIPLE PURCHASE JACK.

Application filed May 18, 1922. Serial No. 561,848.

To all whom it may concern:

Be it known that I, JAMES DRONSFIELD, a subject of the King of Great Britain and Ireland, residing at Atlas Works, Oldham, in the county of Lancaster, England, have invented new and useful Improvements in Multiple Purchase Jacks, of which the following is a specification.

This invention relates to an improved double or multiple purchase jack for application to the shafts of cylinders or doffers or the like requiring to be clothed, as for example, for use with relation to card-mounting machines or other apparatus. The purpose of the jack is to allow of hand rotation through gear from a hand lever as is known.

The improved jack is of the accommodating type, that is, applicable to shafts of varying diameter, as for example shafts between $1\frac{3}{4}$ " and $2\frac{1}{4}$ ", the same jack serving over the desired range of diameters as well as being self-centering and self-contained and giving the desired purchase.

The attached drawings illustrate the construction of the improved multiple purchase jack, and, in said drawings:

Fig. 1 shows a side elevation of the jack, with the actuating handle removed;

Fig. 2 is a sectional plan view, taken on the line 2—2 of Fig. 1.

Fig. 3 is a view of the main flanged casting or wheel showing the jaws fully closed to suit a shaft for example of $1\frac{3}{4}$ " diameter, the jaw structure being indicated in section.

Fig. 4 shows a similar view but with the jaws fully open to suit a shaft for example of $2\frac{1}{4}$ " diameter.

Fig. 5 is a detail sectional view taken on the line 5—5 of Fig. 4, looking in the direction of the arrows.

I make use of a main flanged casting or wheel *a* which is adapted to be rotated and which has an exterior ring of teeth *a'* and a flange *a''* of less diameter than the pitch circle of the ring or teeth, and such flanged casting is bored to a considerable diameter. Combining with such main flanged casting or wheel *a* is a second or auxiliary flanged casting *b* which is also bored and which is fixed to the first flanged casting by studs *c* or otherwise. The annular flange *b''* of the casting *b* is cut away at two diametrically opposite points at that edge thereof which abuts against the casting *a*, so as to form

between said flange and the casting *a*, a pair of segmental slots *b'* (best shown in dotted lines in Figs. 1 and 4) adapted to act as guides for a pair of fulcrumed levers *d* about to be described, it being understood that said levers have a sliding fit in said slots. These fulcrumed levers *d*, *d* have each a pivoted cranked extremity *d'*, *d'* (the pivotal points *d²*, *d²* being on the first mentioned flanged casting or wheel *a*) and are oppositely arranged, the levers *d*, *d* lying substantially parallel one to the other. The central portions of such levers are thicker and form a sort of vice or jaw, said levers being cut away in such a manner and their fulcrumed points so disposed as to render them suitable for engagement with any size of shaft to be driven within certain limits; that is to say, the pivotal centers *d²* of the levers *d* are so located that they always coincide with a line which passes through the center of the shaft which is to be acted upon by the jack when the latter is in position on said shaft, regardless of the diameter of the shaft. The prepared jaws may be provided each half with two dies or bits *e*, *e* (that is four in all) the same being secured by studs *e'*, *e'* or otherwise. The jaws are bored right through at two places vertically or at right-angles to their length, and non-rotatable bolts or studs *f*, *f* turned to two diameters are used each surrounded by a coiled spring *f'* applied around the smaller diameter of each bolt, each spring abutting against a provided shoulder *f²*. Nuts *h^{*}* and washers are applied to each bolt as shown. By turning the nuts *h^{*}* in one direction or the other, the jaws can be caused to grip or release a shaft of any diameter within the range of the jack. In order to provide for the pivotal action of the levers *d*, the openings in one of said levers through which the bolts *f* pass are of larger diameter than said bolts, thereby to permit the levers to swing on their pivots when acted upon by the nuts *h^{*}*, the levers being guided in their movements by the slots *b'* hereinbefore described. The central bore of the two castings is of such size as to allow ready access to the adjusting nuts *h^{*}* which are at all times ready to hand.

Fitting the provided flanges *a''*, *b''* on the two castings *a*, *b* already mentioned, are two shrouds or cover plates *g*, *g'* which are bored to fit the turned flanges *a''*, *b''*, as will

be understood. In addition, these shrouds are bored adjacent one extremity thereof for the reception of a stud h , which is shouldered so as to retain said shrouds spaced apart, and which carries a check pawl h' adapted to cooperate with a ratchet wheel hereinafter described. The stud h also passes through a head h^2 , which is secured to the upper end of a supporting rod or croth h^3 , the lower end of which fits into a pedestal or socket h^4 on the floor, in the usual manner. Between the stud h and the periphery of the castings a and b the shrouds are bored for the reception of a shaft or axle i which carries the turning handle or lever i^2 and sprocket wheels (as for example two sprocket wheels j) for the pitch chain which works the screw for the mounting mechanism. On the same shaft or axle is a small pinion i^3 and a ratchet wheel i' for the pawl h' before mentioned. The small pinion i^3 gears with a larger pinion k mounted on a shaft k' in a third bore in the shrouds, and, on the same shaft k' is a small pinion k^2 which gears with the teeth on the exterior of the main flanged casting or wheel a whereby the required purchase from the lever handle i^2 to the locked gripping vice or jaws engaging the shaft is obtained. The fourth bore is for the spacing stud l at the other extremity of the shrouds.

Obviously the arrangement of the actual gear may be varied.

35 It is clear that the shrouds mask the power multiplying gear and the whole construction gives a very compact form of jack.

40 The improved jack is self-centering, accommodating, easily applied and removed, powerful and yet simple. It will be readily understood that when a shaft is gripped between the jaws e of the levers d , manual rotation of the shaft i by means of the lever i^2 will be transmitted through the medium of the gearing i^3 , k , k^2 and the toothed periphery a' of the flanged casting a , to the combined castings a , b , thus rotating the shaft held by the levers. At the same time, the rotation of the shaft l may be transmitted by means of a chain (not shown) engaging one of the sprocket wheels j , to any desired point, such, for instance, as the screw shaft of a card-mounting machine.

45 I declare that what I claim is:

55 1. A multiple purchase jack, comprising concentric castings, oppositely arranged lever elements, fulcrumed between said castings, said castings having means for guiding the lever elements in their movements, shaft-gripping jaws carried by said lever elements, means for adjusting the jaws toward and from each other thereby to accommodate shafts of varying diameters, an actuating handle, and gearing between said

handle and castings for transmitting rotary motion of the handle to said jaws. 65

2. A multiple purchase jack comprising a casting, a pair of gripping elements fulcrumed on said casting, a second casting secured in concentric relation with the first casting, guide ways in the castings for permitting movement of the gripping elements, threaded bolts carried by said gripping elements for clamping them upon a shaft to be gripped, a pair of shrouds for supporting said castings, a rotatable handle carried by said shrouds, and gearing between said handle and castings for transmitting rotary motion of the handle to said gripping elements. 70

3. A multiple purchase jack, comprising a casting, a concentric adjustable vice structure having two lever elements, each of said elements having a cranked extremity fulcrumed on said casting, a second casting secured to said first casting in concentric relation therewith, guide-ways in the castings for the fulcrumed lever elements, said lever elements being provided with jaw recesses, threaded members for adjusting the fulcrumed lever elements toward and from each other, shrouds supporting said concentric castings, an operating handle carried by the shrouds, and gearing between said handle and castings for transmitting motion from the handle to the lever elements. 80

4. A multiple purchase jack, comprising a pair of concentric castings, a pair of fulcrumed elements disposed between said castings, gripping jaws carried by said fulcrumed elements, threaded bolts passing through the fulcrumed elements for adjustably connecting them, guide ways in the concentric castings for guiding the fulcrumed elements, shrouds supporting said castings, said shrouds being interconnected, gear wheels carried by said shrouds and adapted to rotate said castings, and means for operating said gear wheels. 90

45 5. A multiple purchase jack, comprising a casting, a pair of levers fulcrumed on said casting and provided with self-centering gripping jaws, threaded bolts for adjusting the jaws toward and from each other, a second casting secured in concentric relation with the first, means for guiding the fulcrumed levers, shrouds for supporting the concentric castings, gear wheels supported by said shrouds and engaging said castings for rotating the gripping jaws, a chain sprocket supported for rotation in said shrouds, and an operating handle adapted to actuate said gear wheels and sprocket. 105

55 In testimony whereof I have signed my name to this specification. 115

JAMES DRONSFIELD. 125
